UNITED STATES PATENT OFFICE.

LE ROY W. ARTHUR, OF LOWVILLE, NEW YORK.

DESIGN FOR A PILLOW.

45,782.

Specification for Design.

Patented May 19, 1914.

Application filed January 20, 1914. Serial No. 813,335. Term of patent 7 years.

To all whom it may concern:

Be it known that I, LE ROY W. ARTHUR, a citizen of the United States, residing at Lowville, in the county of Lewis and State of New York, have invented a new, original, and ornamental Design for Pillows, of which the following is a specification, reference being had to the accompanying drawings, forming part thereof.

Figure 1 is a perspective view of a pillow showing my new design. Fig. 2 is an enlarged detail perspective of a portion of the pillow covering, and Fig. 3 is a sectional view on line 3—3 of Fig. 2.

I claim:

The ornamental design for a pillow, as shown.

LE ROY W. ARTHUR.
